UNITED STATES PATENT OFFICE

2,469,054

STAPLING MACHINE

Werner Schafroth, Brookline, Pa., assignor to International Staple and Machine Company, Clifton Heights, Pa., a corporation of Pennsylvania

Application November 19, 1945, Serial No. 629,354

10 Claims. (Cl. 1-49)

1

This invention relates to stapling machines and particularly to the type of machine which is used to secure the flaps or ends of closed cartons or containers where the stationary anvil cannot be used.

The invention is an improvement over similar machines of my prior patents, No. 2,080,634, dated May 18, 1937, and No. 2,234,898, dated March 4, 1941, in that the piercing anvils are directly actuated by positive links and levers instead of cams or other means, and by applying the force through lever action instead of cams, the life of the anvils and other operating parts is considerably extended.

The stapling machine of the type with which this invention is concerned includes, as characteristic elements, a pair of penetrating anvils that are actuated by suitable operating instrumentalities, and these are guided by appropriate cam tracks in a sliding plunger to pierce the material being stapled and cause the anvils to assume a position whereby driving of the staple thereagainst will effect a clinching of the staple legs.

The purpose of the invention is to provide mechanical means for actuating staple clinching anvils through an arc of about 100 degrees, holding them in the extreme or clinching position, and then returning the anvils to their original positions with a positive and, at the same time, easy movement, in which wear of the operating parts is reduced to a minimum.

Due to the complex nature of the movement which is imparted to the penetrating anvils during their piercing operations, it is necessary to provide links and levers directly connected to the anvils and a plunger with cam tracks for actuating the links and levers. In view of the fact that the staple itself closely follows the movement of the penetrating anvils, excessive wear is created upon the cam tracks associated with the anvils as in the prior patents, whereas, by applying the force through the direct action of links and levers, this wear is eliminated.

The object of this invention is, therefore, to provide an improved stapling machine which actuates anvils to the clinching position on the opposite side of materials to be secured by the staples, and then forces the staples through the layers of material and against the anvils, which results in the clinching operation forcing the ends of the staples upward against the inside surfaces of the material.

More in detail this invention has in view as a further objective, the provision of a stapling

2

machine of the type noted which includes a movable guide plunger with a lever forcing the plunger downward together with associated operating instrumentalities that cause the plunger to be moved into position, whereby levers pivotally mounted on the casing and connected to anvils by links, are actuated by cams on the levers extending into cam tracks in the plunger to force the piercing anvils through the material, and assume their ultimate position prior to the driving of the staple.

Associated with this phase of the stapling machine is an extremely important objective which aims at the provision of a machine in which the operations of the penetrating anvils, staple guide plate and staple driving mechanism are accurately and positively synchronized so as to insure of proper operation of the machine.

Yet another object is associated with this phase of the invention and deals with the provision of novel and improved driving connections between the penetrating anvils and the operating instrumentalities therefor.

In order to meet present day conditions prevailing in the manufacture of cardboard cartons, and other similar packages which are intended to be closed by the stapling machine of this invention, and particularly in view of the toughness of the materials which must be pierced in order to carry out the stapling operations, it is necessary that the operating instrumentalities of the machine be effective to drive the penetrating anvils and the staple driving mechanism with extremely high velocity.

35 The creation of these high velocities gives rise to the setting up of a large number of sharp shocks and jars, which, if taken up by the machine alone, greatly reduces the service life thereof.

40 Accordingly the invention has in view, as a highly important objective, the provision of an arrangement in which the material being operated upon (such as the flaps of a corrugated cardboard carton) takes up a large portion of the shocks and jars which are an inevitable incident to the operation of the machine.

Yet another highly important object of the invention is the provision of a novel and improved casing structure that is designed to house the various means, mechanisms and instrumentalities making up the machine of this invention.

50 More in detail the invention has in view the provision of a casing structure which serves to operatively mount various parts of the mechanisms included therein. The casing structure

must be readily assembled and disassembled as occasion demands, and an important phase of the invention is the novel constructional features imparting these properties thereto. It is important that the casing structure be so designed that the machine may be readily manipulated and handled under conditions of practical usage.

Various other more detailed objects and advantages such as arise in connection with the building, design and operation of a stapling machine in accordance with the above noted objectives will in part become apparent, and in part be herein-after stated, as the description of the invention proceeds.

The invention, therefore, comprises a stapling machine including a pair of penetrating anvils pivotally mounted in the lower part of the machine, links rigidly attached to the anvils through the pivotal mounting levers pivotally attached to the links and fulcrumed in the machine upon a sliding plunger having cam tracks in which cams on the said levers extend, a staple feeding plate on the said plunger timed to drive a staple through material upon which the machine is placed and against the anvils after the anvils have moved into clinching position, a handle for operating the said plunger, and suitable staple feeding means.

For a full and more complete understanding reference may be had to the following description and accompanying drawings wherein

Figure 1 is a view showing a side elevation of the stapling machine with the head or vertical section shown in section.

Figure 2 is a view showing a front elevation on line 2-2 of Figure 1 with the front plate removed.

Figure 3 is a similar section looking in the opposite direction with the back plate removed showing the plunger moved downward to the position in which the anvils have been moved to the clinching position, and the plunger is in the position of starting a staple downward.

Figure 4 is a similar view showing the plunger at the extremity of its downward movement in which the ends of the staples are clinched against the anvils.

Figure 5 is a detail illustrating one of the anvils with the link omitted at the end of the shaft thereof.

Referring now to the drawing wherein like reference characters denote corresponding parts, a stapling machine made in accordance with this invention comprises a casing structure for housing the various parts of the operating mechanism which is formed with a vertical section 10 and a supporting leg 11 having a foot 12, as shown in Figure 1, which provides supporting means holding the vertical section perpendicular to the base, or to the surface upon which the machine may be used.

The vertical section of the machine is formed with a comparatively open slot or central hole, having a guiding partition 13 in the lower part thereof, and this is provided with a front plate 14 against which staples 15 are resiliently held by a follower 16, with a spring 17 urging it toward the staples.

It will be understood, however, that the staples may be continuously fed or yieldingly held against the plate 14 by any other means.

Anvils 18 and 19 are formed with integral shafts 20 and 21 which are rotatably mounted in the lower end of the partition 13 and provided at their opposite ends with links 22 and 23, which

are pivotally connected to levers 24 and 25 through pins 26 and 27, and these are pivotally connected to upper links 28 and 29 through pins 30 and 31 on the inner ends of which rollers 32 and 33 are mounted which extend into cam tracks 34 and 35 in the sliding plunger or slider 36. The opposite ends of the links 28 and 29 are pivotally held on a pin 37, which is stationary, in a front wall 38 of the vertical part of the casing.

The upper end of slider 36 is formed with a slot 39 having ears 40 and 41 at the sides in which an operating lever 42 is pivotally mounted on a shaft 43. At the upper end of the lever 42 is a handle 44 and at the lower end is a link 45 by which it is fixedly attached to ears 46 through a pin 47.

This end of the lever 42 is pivotally attached to the link 45 through a pin 48, and it will be noted that as the upper end or handle of the lever is moved downward in the direction of the arrow, the connection at the pin 48 will move outward and then slightly inward permitting the shaft 43 to travel downward in a straight or perpendicular line.

On the inner surface of the slider 36 is a plate 49 which, when the slider is moved downward, engages a staple and forces the staple downward through layers of material on which the machine is placed and against the inner or clinching surfaces 50 and 51 of the anvils, thereby causing the ends of the staple to assume the clinching positions illustrated in Figure 4.

The anvils may be of any type or design. However, it is preferred to use anvils as illustrated in Figure 5 in which the body portions 18 and 19 are integral with the shafts 20 and 21 and their peripheries are described in an arc with the center of the radius corresponding with the center of the shaft. The piercing ends 52 of the anvils are preferably pointed, as shown.

The casing may be fabricated with back and front plates 10 and 38, and end plates 53 and 54, as shown, or may be formed in any manner. The upper portions of the plates 10 and 38 are provided with receiving slots 55 and 56, respectively, to receive the lever 41 as the lever is operated.

While the mode of operation of each of the above described parts will be understood from the foregoing specification, a comprehensive description illustrating the operation of the machine is hereinafter set forth.

In use the machine may be provided, as shown and described, and with staples resiliently held against the plate 14 by a follower, as shown and described, and with the machine placed against the surface of a container, the handle may be moved toward the base and this will actuate the slider or plunger 36 with its associated parts, and as the slider starts downward, it will first draw the rollers 32 and 33 inward along the horizontal portions of the cam tracks 34 and 35 and this motion will cause the links 22 and 23 to move from the position shown in Figure 2 to their respective dotted positions, shown in Figures 3 and 4, and as these links are fixedly mounted on the shafts 20 and 21, they will rotate the anvils so that their points will pierce material upon which the machine is placed, and continue to move downward through the material to the position illustrated in Figure 3.

At this point the plate 49 will engage a staple, as shown in Figure 3, and force the staple downward in the staple track so that the points thereof will pass through the material, and as the

downward action is continued, the ends of the staple will engage the curved surfaces 50 and 51 and follow these surfaces around to their respective positions, illustrated in Figure 4, thereby clinching the ends of the staples against the under surface of the material. As the handle is returned to the upper position, the plunger will be drawn upward and the anvils will be withdrawn through the openings in the material through which they entered.

While preferred specific embodiments of the invention are hereinbefore set forth, it is to be clearly understood that the invention is not to be limited to the exact constructions illustrated and described, because various modifications of these details may be provided in putting the invention into practice within the purview of the appended claims.

What is claimed is:

1. A stapling machine comprising a casing, anvils rotatably mounted in the lower part of the casing and positioned to extend beyond the casing when rotated, arms fixedly attached to the anvils extending upward into the casing, means connected to said arms for operative movement thereof to rotate the anvils to operative positions, and means driving staples from the casing against said anvils, said anvil rotating means and said staple driving means being operated in the sequence that the anvils pierce the material against which the machine is placed, and the staple driving means thereafter clinches the staples forced through the material and against the anvils.

2. A stapling machine comprising a casing, a staple track in said casing for supporting staples, rotatable anvils positioned at one end of said track and adapted to extend beyond the casing, arms integral with said anvils and extending therefrom, a slider in said casing, means operatively connecting said slider to the arms of the anvils, means on said slider for forcing said staples into grooves formed in the anvils, the actuation of said slider effecting first the piercing of the material by the anvils and retaining them in a clinching position during the period the staples are forced through the material and against the anvils.

3. A stapling machine comprising a casing, a staple track in said casing, rotatable anvils positioned at one end of said track and adapted to extend beyond the casing, arms adapted to rotate said anvils and extending therefrom, a slider in said casing having cam tracks therein, rollers extending into said cam tracks, links attached to said rollers and casing, and other links attached to said rollers and said arms for actuating the anvils through said arms.

4. A stapling machine comprising a casing, a staple track in said casing, rotatable anvils positioned at one end of said track and adapted to extend beyond the casing, arms adapted to rotate said anvils and extending therefrom, a slider having L-shaped cam tracks therein, rollers extending into said cam tracks, links attached to said rollers and casing, other links pivotally attached to said rollers and said arms for actuating the anvils through the arms.

5. A stapling machine comprising a casing, a staple track in said casing, rotatable anvils mounted on fixed axes at one end of said track and adapted to rotate said anvils and extending therefrom, a slider having cam tracks therein, a series of links pivotally mounted in said casing

connected to the arms of the anvils, and a toggle arrangement for actuating the links through the cam tracks of the slider.

6. A stapling machine comprising a casing, a staple track in said casing, rotatable anvils mounted on fixed axes at one end of said track and adapted to extend beyond the casing, arms adapted to rotate said anvils and extending therefrom, a slider having cam tracks therein, a series of links pivotally mounted in said casing connected to the arms of the anvils, and rollers on said links extending into said cam tracks for operating the levers.

7. A stapling machine comprising a casing, a staple track in said casing, rotatable anvils mounted on fixed axes at one end of said track and adapted to extend beyond the casing, arms adapted to rotate said anvils and extending therefrom, a slider having cam tracks therein, a series of links pivotally mounted in said casing connected to the arms of the anvils and constituting a system of toggle members, and rollers positioned at sliding points of said first links actuated by said cam tracks for operative movement of the links and anvils.

8. A stapling machine comprising a casing, a staple track in said casing, rotatable anvils positioned at one end of said track and adapted to extend beyond the casing, arms adapted to rotate said anvils and extending therefrom, a slider having cam tracks therein, a set of links pivotally attached to the arms of the anvils, another set of links pivotally mounted on a fixed pin of the casing and pivotally connected to said first mentioned links, and rollers on said last mentioned links extending into the cam tracks of said slider.

9. A stapling machine comprising a casing, a staple track in said casing, rotatable anvils positioned at one end of said track and adapted to extend beyond the casing, arms adapted to rotate said anvils and extending therefrom, a slider in said casing, first links pivotally attached to the arms of the anvils, second links slidably connecting the first links to a fixed point of the casing, and a mechanism including a handle and lever associated with said link system for operative movement of said link system to rotate said anvils.

10. A stapling machine comprising a casing, anvils rotatably mounted in the lower part of the casing and positioned to extend therebeyond when rotated to an operative position, arms fixedly attached to the anvils extending upwardly into the casing, staple driving means for clinching a staple against said anvils, said anvil rotating means and said staple driving means being connected by a slider operated by a system of links connected in a toggle arrangement, one set of links being pivotally attached to said anvil arms, and to rollers adapted to move vertically and laterally in cam tracks provided in said slider, a second set of links having one of their ends connected to a stationary pin carried by said casing and their other ends attached to the roller ends of said second set of links, staple feeding means controlled by said slider, and a lever for reciprocating said slider in a plane vertical to the casing, whereby the reciprocation of said slider is translated through said link system to rotate said anvils and clinch a staple thereagainst at the extreme downward movement of the slider.

WERNER SCHAFROTH.
